UNITED STATES PATENT OFFICE.

HARVEY A. MARTIN, OF BRADY, TEXAS.

DRILL-BIT SWELLING AND DRESSING APPARATUS.

Application filed August 11, 1921. Serial No. 491,492.

To all whom it may concern:

Be it known that HARVEY A. MARTIN, a citizen of the United States of America, residing at Brady, in the county of McCulloch and State of Texas, has invented new and useful Improvements in Drill-Bit Swelling and Dressing Apparatus, of which the following is a specification.

The object of the invention is to provide simple and efficient means whereby a drill bit of the type used in deep well drilling in connection with drill guards or in like spudding operations, and which in practice become circumferentially worn and thereby reduced in diameter may be swelled to gauge and sharpened or dressed at intervals without resorting to the tedious, laborious and time consuming operation of beating or hammering the same with sledges, as in the ordinary practice, after heating the bit to render it workable, and which operation by reason of the time necessarily consumed therein involves the repeated heating or reheating of the same; and more particularly it is the object in this connection to provide a swelling and dressing apparatus by the use of which the drill may be properly reshaped with a single heating thereof and restored with greater accuracy than has heretofore been possible to its original condition; and with these objects in view the invention consists in a construction and combination of parts of which a preferred embodiment is shown in the accompanying drawings, wherein:

Figure 1 is a side view of an apparatus embodying the invention.

Figure 2 is a horizontal section on the plane indicated by the line 2-2 of Figure 1.

Figure 3 is a vertical section on the plane indicated by the line 3-3 of Figure 1.

Figure 4 is an elevation showing a slightly modified arrangement of the power applying means.

Figure 5 is a sectional view in detail of the anvil.

Figure 6 is a detail in perspective of the same.

The apparatus consists essentially of an anvil 10 shaped to form a die corresponding in gauge or dimensions with the drill head when in its proper condition and adapted to receive the drill 11 as indicated in Figure 1, said anvil being preferably arranged in a tempering tray 12 beneath a bearing lever 13 adapted to bear at an interme-

diate point upon the end of the drill bit 11, being fulcrumed terminally as indicated at 14 to a suitable standard or support 15 and having suitable power or operating mechanism 16 connected with its free end as a means of swinging the lever downward to force the bit face into the die member of the anvil, it being understood that the drill bit at its operative end is heated as a step preliminary to its arrangement in the die, so that longitudinal pressure applied to the bit through the actuation of the bearing lever will swell the bit while the sharpening of the edges thereof and the truing or dressing of the bit circumferentially to insure a cylindrical exterior contour may be effected by means of sledges striking the side surfaces of the bit and reducing them to a condition wherein they are flush with the convex side surfaces 17 of the anvil.

In the construction illustrated the standard or support 15 is of channel form with provision for pivoting the bearing lever at spaced points in the length thereof as by 80 having a plurality of openings 18 arranged in series and adapted for selective engagement by the pivot pin 14, to suit drill bits of different lengths.

Also preferably the anvil is of hollow construction as shown in detail in Figure 5 to provide for establishing and maintaining a circulation of the cooling agent therethrough during the shaping of the drill and particularly the lateral hammering and dressing thereof, suitable supply and outlet tubes 19 and 20 being arranged in communication with the interior of the anvil, and the outlet preferably discharges into the tempering tray 12 having an overflow outlet 21 and a suitable rack 22 upon which the head of the drill bit may be raised for tempering and cooling after it has been shaped in the die.

The form of power mechanism illustrated 100 in Figure 1 contemplates a tension bar 23 pivotally anchored to any suitable object such as the tank or tray 12 at 24 and connected by a rocking lever 25 with an operating bar 26, the rocking bar being intermediately connected by a link 27 with the bearing lever, and means being provided for applying a tensile strain to the operating bar, such as an operating ratchet lever 28 engaging a rack 29, the lower end of said operating bar being anchored as indicated at 30 and both the tension and operating bars 23

and 26 being constructed for adjustable connection with the terminals of the rocking lever 25 as by having series of openings 23^a and 26^a respectively for engagement selectively by pivot pins 23^b and 26^b. This adjustment obviously is designed to compensate for any required adjustment of the pivot 14 to suit the length of the drill bit to be treated.

10 It will be understood that the power applying mechanism as indicated is merely typical of that which may be employed in this connection and as shown in Figure 4 a modification thereof may consist in employing the operating bar 31 as a means of directly operating the bearing lever, the operating means 32 thereof being similar to those above described and the terminals of said bar being respectively anchored as indicated at 33 and adjustably connected as at 34 to the bearing lever 35. In this connection as heretofore described the operating lever may be provided with a series of openings 36 for selective engagement by the pivot pin 37.

15 In practice, as will be obvious from the foregoing description, the operation of swelling or enlarging and dressing a drill consists in heating the same as in the ordinary practice to a condition rendering it malleable and then applying the face of the bit to the die with the rear end of the bit in the path of the movement of the bearing lever, and then applying sufficient power to the lever to 20 force the head or operative end of the drill bit into the die and spread or swell it to fit the accurately gauged face of the latter. In this spreading or swelling operation it is common for the bit to acquire a slight irregularity of form which may readily be 25 corrected while under pressure and in the die by the application of the strokes of the mauls or sledges to the exposed side surfaces thereof adjacent to and above the convexed 30 faces 17 to reduce the side surfaces of the bit to a condition flush with the surfaces 17 which being cylindrical will properly define 35

the cutting edges of the bit face and result in a sharpening of the edges necessary to produce efficiency in drilling. The final tempering of the bit as in the ordinary practice 40 reduces it to a condition ready for subsequent use and as the operation of spreading or swelling and dressing can be accomplished in a comparatively short time a single preliminary heating of the drill is ordinarily sufficient and therefore the successive reheating of the same, as in the ordinary practice, and the loss of time incident thereto are 45 eliminated.

50 Having described the invention, what is claimed as new and useful is:—

1. A drill bit swelling and dressing apparatus having an anvil provided with a die 55 for the reception of the cutting head of the bit, a bearing member for imparting longitudinal movement of the bit toward the die, and means for actuating the bearing member, the bearing member consisting of a lever terminally mounted for pivotal movement 60 and adapted for engagement at an intermediate point of its length with the rear end of the drill bit.

2. A drill bit swelling and dressing apparatus having an anvil provided with a die 65 for the reception of the cutting head of the bit, a bearing member for imparting longitudinal movement of the bit toward the die, and means for actuating the bearing member, said anvil being arranged in a tempering tray having means for producing a 70 circulation of tempering medium.

3. A drill bit swelling and dressing apparatus having an anvil provided with a die 75 for the reception of the cutting head of the bit, a bearing member for imparting longitudinal movement of the bit toward the die, and means for actuating the bearing member, the anvil being of hollow construction 80 and having means for maintaining a circulation of a cooling agent therethrough.

85 In testimony whereof he affixes his signature.

HARVEY A. MARTIN.
